UNITED STATES PATENT OFFICE

FRANK C. SIMMS, OF EAST PALESTINE, OHIO

PYROMETER TUBE

Application filed July 14, 1928. Serial No. 292,859.

My invention relates to temperature measuring devices, and particularly to pyrometer tubes.

An object of my invention is to provide a unitary structure for a composite pyrometer tube that shall permit of the tube being quickly inserted in and withdrawn from the chamber of a furnace without danger of breaking or cracking.

10 Another object of my invention is to provide a unitary pyrometer tube structure that shall embody a gas tight inner refractory member, a heat-equalizing intermediate ceramic member, and an outer highly refractory and gas and slag resistant member. These three elements are preferably made each in the form of a tube, closed at one end and open at the other, and in intimate contact with each other over their engaging surfaces.

20 In practicing my invention, I provide a laminated tube structure comprising an inner tube closed at one end, made of ceramic material and fired or burned at such heat as to ensure vitrification, an intermediate tube 25 also closed at one end molded or placed on the inner tube and composed of such ceramic materials as to permit of reasonably slow penetration thereof by heat, and an outermost coating or tube of suitable thickness, and composed of a ceramic material which will prevent slag from penetrating the bodies of the other tubes.

In the single sheet of drawings,

Figure 1 is a view, in longitudinal section, 35 of a pyrometer tube embodying my invention, and,

Fig. 2 is a view, in vertical lateral section of a furnace, shown generally only, with which is associated the device embodying my 40 invention.

The pyrometer tubes used heretofore have been made of a material which had to be handled very carefully in actual use, the tube being inserted in and withdrawn from a high 45 temperature furnace chamber at a very slow rate of movement in order to prevent fracture thereof. If a tube of this kind was inserted into a furnace chamber very quickly the effect of the high heat was such as to cause 50 the tube to crack or break.

Referring more particularly to Fig. 1 of the drawings, I have there illustrated a laminated pyrometer tube 11 embodying an inner tube 12 which is preferably made of a hard, dense clay, such as is used for porcelain articles and which has been fired at a temperature of approximately 2000° F.

An intermediate tube 13 is located there-around and in intimate engagement therewith, the material of this tube being a mixture of comminuted fused alumina, a high temperature clay, and a small amount of a suitable binder such as dextrine. I prefer to use a mixture of 30% of high temperature clay and approximately 70% of fused alumina, although I desire it to be understood that these proportions are illustrative only and may be departed from to a certain extent. Enough suitable binder is added to the finely divided clay and the fused alumina to make a relatively moist mixture of the general consistency of heavy cream.

The tube 12, which may be of any desired thickness on the order of from $\frac{1}{8}$ to $\frac{3}{8}$ inch wall thickness and which is closed at one end as shown, may be dipped into the moistened mixture of clay and alumina a sufficient number of times to provide a relatively thick closely adherent coating around the exterior of the tube 12. It may be necessary to permit the coating obtained by each dipping to dry for a short period in air before another coating is applied. A sufficient number of dippings are made to provide a relatively thick coating or tube 13, which thickness may be equal to or slightly greater than the thickness of the wall of tube 12. I may also mold the fused alumina and clay coating around or on the inner tube.

An outer tube or coating 14 is provided and I may make this of a ceramic material suitable for the desired purpose, such as magnesite or zirconium, the method of application being substantially the same as was hereinbefore set forth in connection with the coating 13. The outer layer or coating may be applied as soon as the last layer of coating 13 has been thoroughly dried.

I prefer, as noted above, to fire the porcelain tube 12, which I make in any suitable

or desired manner well known in the art before applying thereto the two outer tubes or coatings as explained above. After these plurality of coatings have been thoroughly dried in air I place the tube in a suitable furnace chamber operating at a temperature of not less than 2000° F and possibly up to 3000° F. The firing is continued until the inner tube 12 has been vitrified or re-fused to a greater extent than occurred during its initial firing, whereby it is rendered substantially gastight.

Referring to Fig. 2 of the drawings, I have there illustrated a furnace structure 15 comprising a plurality of walls of heat-insulating and high-temperature-resisting bricks or blocks surrounding a furnace chamber 15a. Any suitable means (not shown) may be provided to heat the furnace chamber. An opening 16 is provided in one of the walls which is of such size as to receive the pyrometer tube structure 11.

A thermocouple 17 is located within the pyrometer tube assembly 11, the tube extending sufficiently far into the furnace to subject the thermocouple joint to the operating temperature existing in the chamber. Suitable indicating means (not shown) are connected to the two wires of the thermocouple to indicate the temperature, all as well known in the art.

My improved laminated pyrometer tube structure is particularly adapted for use in furnaces in which special processes are being effected which give rise to fumes which attack ordinary ceramic materials, or in furnaces containing slags which attack ordinary ceramic materials. The innermost tube 12 I find to be substantially gas-proof, the intermediate tube or coating 13 having a relatively low co-efficient of expansion when heated, and having also a relatively high thermal conductivity, permits the heat to flow therethrough slowly enough to prepare the innermost tube and protect it against the excessive temperature changes to which it would be subjected if it were not thus protected. The second coating acts also as a temperature equalizing means so that the heat which reaches the innermost tube is substantially uniformly distributed, thereby avoiding the possibility of breakage of the inner tube by reason of one portion thereof being at a temperature different from that of another portion. Finally, the outermost coating 14 pro-

vides a slag, gas, and fume resistant coating so that the unitary tube structure embodying my invention can be used a relatively large number of times without any appreciable sign of the material having been attached. I find it possible to insert a tube of this kind quickly into a furnace or to withdraw it quickly from a furnace without danger of such thermal shock as would ordinarily result in fracture of a single layer tube.

The intermediate coating or tube 13 has

such thermal conductivity as will appreciably slow down the rate of penetration of the heat, but does allow all of the heat to reach the innermost tube and therefore the thermocouple within a very short time.

The device embodying my invention thus comprises a unitary laminated tube structure comprising a plurality of closely united tubes or coatings, each one being designed to meet a specific requirement. First, an inner tube of such hardness and density as to prevent gases from traversing the walls thereof. Second, an intermediate tube of such material and characteristics as to withstand sudden thermal shock. This tube or lamination absorbs the heat relatively slowly and prevents a sudden heat shock from injuring the inner tube. Third, an outer lamination or tube of a suitable ceramic material adapted to withstand the penetrating action of slag and fumes, to thereby save the other two tubes from the injury which may be caused by slag found in various types of furnaces.

Various modifications may be made in the device embodying my invention without departing from the spirit and scope thereof, and I desire therefore that only such limitations shall be placed thereon as are imposed by the prior art or are set forth in the appended claims.

I claim as my invention:—

1. As a new article of manufacture of the class described, a unitary laminated pyrometer tube structure comprising an inner highly refractory gas-tight tube of ceramic material, an intermediate tube of a refractory material constituting a heat shield for the inner tube, and an outer tube of a slag and fume resistant refractory material, all of said tubes being intimately bonded with each other by firing the outer tubes and the inner tube as a unit.

2. As a new article of manufacture of the class described, a unitary triple wall pyrometer tube structure comprising an inner gas-tight layer of highly refractory ceramic material, an intermediate layer of a refractory material constituting a heat shield for the inner tube, and an outer coating of a slag and fume resistant refractory material, each of said layers being in intimate engagement with an adjacent layer and bonded thereto by firing the outer layers in position upon the inner layers.

3. As a new article of manufacture of the class described, a unitary triple wall pyrometer tube comprising an inner layer of porcelain, an intermediate layer of a mixture of fused alumina and a high temperature clay, and an outer layer of magnesite, each of said layers being in intimate engagement with an adjacent layer, the intermediate and outer layers being coated upon the adjacent inner layer and bonded thereto by firing said layers.

4. As a new article of manufacture of the class described, a unitary triple wall pyrometer tube comprising a doubly fired inner layer of porcelain-like ceramic material, a singly fired intermediate layer of fused alumina and a high temperature clay, and a singly fired outer layer of a slag and fume resistant ceramic material, each of said layers being in intimate engagement with an adjacent layer and bonded thereto by the firing of the outer layers.
